UNITED STATES PATENT OFFICE.

SANDFORD BROWN, OF MONTCLAIR, NEW JERSEY, ASSIGNOR TO HALOWAX CORPORATION, OF NEW YORK, N. Y., A CORPORATION OF NEW YORK.

LEATHER-BELT DRESSING.

No Drawing.

Application filed April 23, 1925. Serial No. 25,439.

The invention relates to improvements in leather belt dressings. An object of the invention is the provision of a composition which will soften the belt and make it pliable and at the same time prevent it from getting gummy on the surface. Another object is the provision of a composition in which well-known belt-dressing ingredients, preferably castor oil and neat's foot oil, are dissolved in a non-volatile solvent which will carry these ingredients well into the body of the leather, where lubrication will be supplied to the inner fibres of the leather as well as those lying close to the surface. Other objects consist in the provision of a dressing having the composition and properties more fully described hereinafter in the following specification, and particularly pointed out in the appended claims.

The above objects are best effected by the use of an oily halogen substitution product of naphthalene, in addition to other ingredients such as castor oil and preferably in addition to both castor oil and neat's foot oil. The halogen substitution product preferably takes the form of mono-chloro naphthalene or of an oily product which as commercially made consists chiefly of mono-chloro naphthalene with the addition of minor proportions of higher chlorine substitution products of naphthalene. Neat's foot oil and castor oil are well known as effective natural lubricants and softeners for leather. Belt dressings are known in which neat's foot and castor oils are incorporated with various solvents which aid in carrying the same into the belt. These solvents, however, are sometimes of such nature as to be injurious to the leather and sometimes are volatile. When such solvents are used the neat's foot and castor oils will not be carried into the body of the leather as far as when the oily halogen substitution product of naphthalene referred to herein is used, and in such cases the surface of the belt is very likely to be left in a gummy condition because of the presence thereon of sticky ingredients such as the castor oil when the solvent has evaporated.

The mono-chloro naphthalene or equivalent material, which I incorporate in the belt dressing, is a solvent for both castor oil and neat's foot oil. This oily substance is non-volatile, has low viscosity and a greater

ability to penetrate the leather than that of either neat's foot oil or castor oil. The mono-chloro naphthalene is itself beneficial to the leather and tends to keep the leather soft in addition to which it water-proofs the leather.

The best results are thought to be obtained when the castor oil and neat's foot oil are both incorporated with the oily chlorinated naphthalene. Neat's foot and castor oils are soluble in this material in various proportions. It is believed that proportions of approximately 33 $\frac{1}{3}$ % of each of the three ingredients preferably present, namely neat's foot and castor oil and mono-chloro naphthalene, are preferable.

When this composition is used, lubrication is apparently supplied to each of the tiny fibres within the body of the leather belt and not merely to the fibres lying close to the surface. This is because of the unusual penetrating qualities of the oily chlorinated naphthalene. It makes the belt soft and pliable and at the same time prevents gumming on the surface of the belt because of the fact that all of the lubricant is apparently carried into the body of the leather. The use of the composition insures the effective delivery of power by the belt by giving the belt pliability which is necessary to insure a good grip on the pulleys, while at the same time the composition introduces into the belt no harmful adhesives which may serve temporarily to make possible the carrying of a load for which the drive was not designed but which are harmful in the long run. It may likewise be noted that the composition will not become rancid and that its use prevents mildew on the belt because of the fact that the chlorinated naphthalene is a germicide and fungicide.

While the composition preferably consists of the use of the three ingredients noted, it is not necessarily limited to the use of these three specific elements, reasonable equivalents of the same being included within the scope of the invention. It should be also noted that, while best results are obtained by the use of both neat's foot and castor oils, the use of one only of these elements, or its equivalents, together with the chlorinated naphthalene oil, is included

within the scope of the invention. In this connection it should be noted that the castor oil is thought to be preeminently the lubricating factor in such a composition, the neat's foot oil serving largely to soften the leather, which property is also possessed by the chlorinated naphthalene oil, and therefore the neat's foot oil can better be omitted from the composition than the castor oil.

10. What I claim is:

1. A belt dressing comprising neat's foot oil, castor oil, and an oily halogen substitution product of naphthalene.
2. A belt dressing comprising neat's foot oil and castor oil dissolved in an oily halogen substitution product of naphthalene.
3. A belt dressing comprising neat's foot oil and castor oil dissolved in an oily chlorinated naphthalene having a low viscosity.
20. 4. A belt dressing comprising neat's foot oil and castor oil dissolved in an oily prod-

uct of low viscosity, consisting chiefly of mono-chloro-naphthalene.

5. A belt dressing comprising about equal proportions of neat's foot oil, castor oil, and 25 an oily halogen substitution product of naphthalene.

6. A belt dressing comprising castor oil and an oily non-volatile halogen substitution product of naphthalene having low 30 viscosity.

7. A belt dressing comprising castor oil and an oily product of low viscosity consisting chiefly of mono-chloro-naphthalene.

8. A belt dressing comprising oily leather 35 lubricating and softening elements dissolved in an oily halogen substitution product of naphthalene.

In testimony whereof I have signed my name to this specification.

SANDFORD BROWN.
